UNITED STATES PATENT OFFICE

2,573,224

RETRACTABLE PILOT FOR RAILWAY
LOCOMOTIVESAlbert M. Schieler, St. Louis, Mo., assignor to
General Steel Castings Corporation, Granite
City, Ill., a corporation of Delaware

Application July 16, 1947, Serial No. 761,233

3 Claims. (Cl. 293—48)

1

The invention relates to railway vehicles and more particularly to pilot structure therefor.

The ordinary locomotive is provided with a coupler at its forward end. In many locomotives the coupler, when not being used, can be retracted within the pilot and a cover plate closes the coupler recess in the pilot and provides a deflecting surface so that objects in the path of the locomotive will be thrown to the side of the track or lifted so as not to become wedged between the track and locomotive front end. Many locomotives still in use have non-retractable couplers and when such a locomotive strikes an object in its path, the object may be wedged between the forwardly projecting coupler and the track and be dragged with the locomotive, often derailing the locomotive and causing derailment of other cars of the train. Many of the locomotives last described are not even equipped with pilots.

One object of applicant's invention is to provide locomotive front end structure, including a pilot and a non-retractable coupler, in which the pilot provides a deflecting surface of the kind described when the coupler is not being used.

Another object is to provide a pilot for a locomotive having a non-retractable coupler, which pilot has a portion below the coupler movable longitudinally of the locomotive to provide a deflecting surface of the kind described extending downwardly from the front end of the coupler when the coupler is not being used.

Other objects will be apparent to those skilled in the art from the following description and accompanying drawings, in which:

Figure 1 is a top view of the forward end of a locomotive provided with a pilot structure constructed according to the invention.

Figure 2 is a front view thereof, with a portion sectioned on the line 2—2 of Figure 1.

Figure 3 is a longitudinal vertical section taken approximately on the line 3—3 of Figure 1.

Figure 4 is a side view of a locomotive pilot structure showing another form of the invention.

Figure 5 is a front view thereof.

Figures 6, 8, 11 and 13 are views similar to Figure 1 of a locomotive pilot structure and show other forms of the invention.

Figures 7, 9, 12 and 14 are views similar to Figure 2 of the pilot structure shown in Figures 6, 8, 11 and 13, respectively.

Figure 10 is a longitudinal vertical section taken approximately on line 10—10 of Figure 8.

In Figures 1-3, the front end of a locomotive framing is provided with a pilot beam 2 mounted

2

ing a pilot member 3 and a coupler pocket 5a. A non-retractable coupler 5 including a head 6 and a shank 7 is pivoted for horizontal movement on a vertical pin 8 in coupler pocket 5a. Pilot member 3 has a forward obstacle deflecting wall 3a recessed centrally at 4 to receive coupler 5.

A pilot element 9 has a forward obstacle deflecting face 9a and is positioned in recess 4 below coupler 5. Pilot element 9 is movable from an inoperative retracted position (shown in dot and dash lines in Figures 1 and 3) substantially within pilot member 3 and rearwardly of the front end of coupler 5, to an extended position (shown in solid lines in Figures 1 and 3) in which a substantial portion of the pilot element extends forwardly of the pilot member and in which face 9a of the pilot element is positioned in substantial vertical alignment with the front end of the coupler.

20 Pilot element 9 preferably has upward extensions 9b which are positioned in recess 4 at the sides of coupler head 6 when the pilot element is in extended position. Extensions 9b restrict lateral movement of coupler 5 and provide additional deflecting pilot surfaces at the sides of the coupler. Extensions 9b move rearwardly within pilot member 3 adjacent coupler shank 7 when pilot element 9 is retracted to provide for lateral pivotal movement of coupler 5 about its pivot 8. In extended position, face 9a of pilot element 9 and its extensions 9b cooperate with wall 3a of pilot member 3 and with the front end of coupler 5 to provide a continuous deflecting surface which throws obstacles, when in the path of the locomotive, to the side so the obstacles do not become wedged between the track and coupler.

Rails 10 on pilot member 3 extend inwardly from its forward face and are received in grooves 11 in pilot element 9. Pilot element 9 is supported and guided by rails 10 as it slides thereon from one position to the other. A piston 12 is connected by a rod 13 to a bifurcated rib 14 on pilot element 9 and is slidably in a cylinder 15 secured to the pilot beam. Pipes 16 admit air under pressure to cylinder 15 to operate piston 12 and move pilot element 9 to retracted and extended positions. Laterally extending pins 17 slidably mounted in pilot member 3 are received in apertures 18 in webs 19 of pilot element 9 and secure the pilot element in selected position. Pins 17 are urged into apertures 18 by compression springs 20 seated against ribs 21 of pilot member 3. Each pin 17 is disengaged from pilot element 9 by a single acting air cylinder 22 connected by a piston rod 23 to a lever 24 connected

at one end to the pin and at the other end to a bracket 25 rigid with pilot member 3. Preferably air is supplied to cylinders 22 and 15 simultaneously so that the pins are withdrawn automatically from pilot element 9 when it is moved from one position to the other. When pilot element 9 has been shifted and the cylinder air pressure is released, springs 20 again thrust pins 17 into locking position.

The pilot structure shown in Figures 4 and 5 is similar to the pilot structure shown in Figures 1-3 with the exception that shiftable pilot element 31 and the associated recess 32 in pilot member 33 are narrower and of different contours than the corresponding parts shown in Figures 1-3. A pair of laterally extending locking pins 34 are provided on each side of the pilot element to hold the pilot element in retracted and extended positions. Locking pins 34 are applied and removed manually and keepers 35 prevent the locking pins 34 from accidental removal. Pilot element 31 is moved from one position to the other by a double acting air cylinder 36 as in the previous embodiment.

In Figures 6 and 7, pilot beam 41 mounts a coupler pocket 42a supporting a coupler 42 for pivotal movement in a horizontal plane about a pin 42b in the coupler pocket. Pilot beam 41 mounts a pilot 43 recessed at 44 and movable from an extended position (shown in solid lines in Figure 6) in which the pilot 43 encloses coupler 42 to a retracted position (shown in dot and dash lines in Figure 6) in which pilot 43 abuts pilot beam 41 and coupler 42 extends forwardly thereof through recess 44. A pair of longitudinally extending cylinders 45 are rigid with pilot beam 41 and slidably receive rearward extensions 46 on pilot 43 to support and guide the pilot as it is moved from one position to the other. An air cylinder 47 connected to the pilot by a piston rod 48 moves the pilot from one position to another. Locking pins 49 extend laterally through guides 45 and extensions 46 and hold pilot 43 in extended or retracted position. Pins 49 may be moved into and out of locking position by air cylinders 50.

In Figures 8, 9 and 10, a pilot beam 51 rigidly mounts a pilot member 52 having a central recess 53. A coupler 56 is attached to pilot beam 51 for pivotal movement in a horizontal plane and extends through recess 53 in pilot member 52. A pilot element 54 in recess 53 below coupler 56 is pivoted to pilot member 52 by a vertical pin 55 and moves from a retracted position (shown in dot and dash lines in Figure 8) within pilot member 52 to an extended position (shown in solid lines in Figure 8) in which pilot element 54 extends forwardly of pilot member 52 and the front end of coupler 56. Pilot element 54 is locked in forwardly extended position by a pin 57 and may be held in retracted position by any suitable means.

In Figures 11 and 12, a pilot beam 61 rigidly mounts a pilot member 62 having central recesses 65 and 65a. A coupler 63 extends forwardly of pilot member 62 through recess 65 and is pivoted at 64 for movement in a horizontal plane to a coupler pocket 64a rigid with pilot beam 61. A pair of pilot elements 66 in recess 65a are pivoted to pilot member 62 below coupler 63 by vertically disposed pins 67 for movement in a horizontal plane from retracted position (shown in dot and dash lines in Figure 11) within pilot member 62 to extended position (shown in solid lines in Figure 11) forwardly of pilot member

62 and the front end of coupler 63. Manually inserted locking pins 68 secure pilot elements 66 in extended and retracted positions.

In Figures 13 and 14, a pilot beam 71 rigidly mounts a pilot member 72 having a central recess 75. A coupler 73 extends through recess 75 and is carried by pilot beam 71 for horizontal pivotal movement. A pair of pilot elements 76 below pilot member 72 extend substantially the entire width of the pilot member and are pivoted thereto by vertically disposed pins 77 at the outer ends of the pilot member for movement in a horizontal plane from retracted position (shown in dot and dash lines in Figure 13) to extended position (shown in solid lines in Figure 13) forwardly of pilot member 72 and the front end of coupler 73. The inner ends of pilot elements 76 intermesh to facilitate retraction of the elements. Vertically disposed spring urged locking pins 78 secure pilot elements 76 in extended and retracted positions.

The movable portions of the pilots in Figures 8-14 may be retracted and extended by power means as shown in Figures 1-7 and the movable portions of the pilots in Figures 1-7 may be retracted and extended manually as shown in Figures 8-14. To facilitate such manual movement, a screw, a winch and cable, or other suitable means, may be used.

The locking pins holding the pilot elements in retracted and extended positions in Figures 1-14 and the pilot element pivot pins in Figures 8-14 must be of sufficient strength to withstand thrusts applied to the pilot elements when striking objects in the path of the locomotive.

In each of the embodiments described, the coupler is pivoted on a fixed support on the pilot beam and the buffing and pulling forces through the coupler are applied directly to the pilot beam and not to the pilot. The pilots are designed for attachment to pilot beams now in use and for using present couplers and coupler pockets. The pilot structures described are effective in deflecting objects in the path of the locomotive to the side so the objects do not become wedged between the coupler and track.

The structures described may be varied substantially without departing from the spirit of the invention, and the exclusive use of those modifications coming within the scope of the claims is contemplated.

What is claimed is:

1. In combination, a railway vehicle frame part, a pilot member mounted thereon and having a forwardly opening recess, a coupler in said recess having a head, a vertical pivot swingingly mounting said coupler on said frame part, a pilot element in said recess below said coupler, upward extensions on said pilot element adjacent said coupler, said pilot element being slidably mounted on said pilot member to move rearwardly relative to said pilot member and coupler to a retracted position in which said extensions are positioned substantially adjacent said pivot, and said pilot element being movable forwardly relative to said pilot member and coupler to an extended position in which said extensions are positioned adjacent the coupler head and restrain swinging movement of the coupler.

2. In railway pilot structure, a stationary portion forming the pilot sides and the top and bottom of a coupler-receiving recess, a pilot center member slidable on said portion beneath said recess to an extended position and to a retracted position, a coupler in said recess including a

shank and a head, an upright pivot pin securing said coupler shank to said stationary portion for lateral swinging movement, said member having upstanding walls at the sides of said coupler head projecting forwardly of said recess at the sides of the coupler head when said member is in extended position, and received within said recess at the sides of said pivot pin when said member is in retracted position.

3. Railway pilot structure as described in claim 2 which includes a fluid pressure cylinder with associated piston connected to the stationary portion and to the pilot center member and operable to move said pilot center member to the extended and retracted positions.
